Attorney

UNITED STATES PATENT OFFICE.

ANTHONY R. SILVIA, OF NEW BEDFORD, MASSACHUSETTS.

SHUTTLE.

1,290,379.

Specification of Letters Patent.

Patented Jan. 7, 1919.

Application filed June 10, 1918. Serial No. 239,189.

To all whom it may concern:

Be it known that I, ANTHONY R. SILVIA, a citizen of the United States of America, and resident of New Bedford, in the county 5 of Bristol and State of Massachusetts, have invented certain new and useful Improvements in Shuttles, of which the following is a specification.

This invention relates to weaving and particularly to shuttles, the said invention having for its object the provision of novel means for facilitating the threading of the shuttle of the type illustrated in the drawing which is known as the "Dandy" shuttle,

15 It has been the common practice to operate the thread hook through the shuttle eye, but in the present invention, the threader or hook is made operable in conjunction with the pot eye of a shuttle.

20 A further object of this invention is to provide novel means for guiding the hook into position so that the thread can be readily applied to the threading implement or hook and pulled through the pot eye as will 25 be readily understood by those skilled in the art.

A further object of this invention is to provide a guide in such relation to the shuttle that it will not interfere with operating 30 parts of the shuttle or materially increase the cost of same.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification 40 wherein like characters denote corresponding parts in the several views, and in which—

Figure 1 illustrates a plan view of a fragment of a shuttle, being partly in horizontal 45 section;

Fig. 2 illustrates a view in elevation, partly in vertical section;

Fig. 3 illustrates a horizontal sectional view of a fragment of the shuttle body showing one embodiment of the invention; and

Fig. 4 illustrates a similar view embodying a modification.

In these drawings 5 denotes the shuttle body, 6 the bobbin recess thereof, and 7 the

pot eye. At the reduced portion of the bobbin recess, one wall thereof is supplied with a shoulder 8 which in its construction may be integral with the bobbin body or it may comprise a block 9 secured to the surface of the bobbin body, the particular requirements being that the edge which faces the pot eye is inclined rearwardly so that a threading implement 10 if inserted in the pot eye comes in contact with the inclined surface of the shoulder and the said inclined surface guides it upwardly so that it will pass above the upper surface of the shuttle where the thread can be applied to it, thus making it possible to facilitate the threading of a bobbin by the tool since the tool can be withdrawn from the pot eye.

In the modification illustrated in Fig. 4, I have produced the inclined shoulder by anchoring a plate 12 in the bobbin body and having a flange 11 extend outwardly from the edge of the bobbin body, the said flange being concaved so that the threading implement will strike the flange and ride up the surface thereof just as it will ride up the shoulder heretofore described.

I claim—

1. In a shuttle, a shuttle body having a bobbin recess and a pot eye extending longitudinally of the shuttle and entering the end of the recess, a shoulder extending outwardly from the side of the recess facing the pot eye, and offset with relation to the axis of said eye, said shoulder being inclined rearwardly to form a camming surface and having its camming surface grooved and adapted to engage a threading implement for guiding the said threading implement beyond the end of the bobbin and above the surface of the shuttle.

2. In a shuttle, a shuttle body having a bobbin recess and a pot eye extending longitudinally of the shuttle and communicating with the bobbin recess, a plate anchored in the bobbin body and projecting into the shuttle recess and forming a shoulder, said shoulder extending portion of the plate having a groove on its operative face and facing the eye and offset with relation to said eye and adapted to guide the end of a threading implement to a point above the surface of the shuttle.

ANTHONY R. SILVIA.
